UNITED STATES PATENT OFFICE.

LENA E. LINHART, OF DAWN, MISSOURI, ASSIGNOR TO THE BUCKEYE INCUBATOR COMPANY, OF SPRINGFIELD, OHIO, A CORPORATION OF OHIO.

MEANS FOR INSULATING SMOKE PIPES.

Application filed September 1, 1925. Serial No. 53,844.

This invention relates to a device for insulating smoke pipes, particularly that part of the pipe which is exposed to outside atmosphere.

The invention has been especially designed for the smoke pipes of stoves employed in brooder houses for chicks, although not necessarily limited to that purpose. In the use of brooder stoves it has been customary to employ a sheetmetal smoke pipe which extends through the roof or through one of the side walls of the brooder house to outside atmosphere and trouble has been caused by the accumulation of tar in the pipe probably caused by the condensation of the gas in that part of the pipe which is exposed to outside atmosphere.

The object of my invention is to overcome that difficulty by insulating that part of the smoke pipe which is exposed to outside atmosphere, a more particular object of the invention being to provide a simple form of insulation for the pipe which can be readily installed on pipes now in use as well as upon pipes of newly erected brooder houses or newly installed brooder stoves.

In the drawings:

Fig. 1 is a vertical section of a brooder house showing a brooder stove and its pipe with my improvements applied thereto.

Fig. 2 is a view of the upper portion of the smoke pipe shown partly in vertical section, with one form of insulating device therefor shown in vertical section.

Fig. 3 is a similar view to Fig. 2, but showing a modified form of insulation.

Fig. 4 is a section on the line 4—4 of Fig. 2.

Referring to the drawings, 1 represents a brooder house of any well known form and 2 the roof thereof. The brooder stove is indicated at 3, this stove being a coal burning stove of well known type. It is usual to place a canopy over the stove but this canopy is not shown in the present instance. The smoke pipe of the stove is indicated at 4 and in the present case passes through an opening in the roof 2, this pipe being formed throughout its length of sheetmetal in the usual way. The pipe extends a considerable distance above the roof into outside atmosphere and it is that portion of the pipe above the roof to which my invention is applied.

Referring to Fig. 2, 5 represents a sheet 55 of metal which is secured to the roof and covers the opening through the roof. This metal sheet is centrally apertured and there is secured to the edges of the aperture by an ordinary sheetmetal joint a thimble-like 60 sheetmetal member 6 preferably of tapered form. When the smoke pipe passes through a slanting roof such as illustrated, this thimble is so formed that the vertical axis thereof will extend vertically and be in co- 65 axial relation with the vertical axis of the smoke pipe 4 and the diameter of the thimble is considerably greater than that of the pipe so as to provide an air space. An outer jacket 7 of sheetmetal has its lower 70 end fitted in telescopic relation with the thimble 6 and extends substantially to the upper end of the smoke pipe 4. A sheetmetal cap 8 closes the upper end of the jacket 7 and is apertured to receive the 75 smoke pipe 4, the cap and pipe having a close fit so as to close the upper end of the space between the pipe and the jacket. In this construction, I have also placed about the upper part of the smoke pipe a covering 80 9 of sheet asbestos or similar material. In the arrangement shown in Fig. 2 it will be seen that the upper part of the smoke pipe is covered with asbestos and will be surrounded by an air space which is open only 85 to the interior of the brooder house so that the air confined therein will be maintained in a more or less heated condition.

In Fig. 3 there is employed the same metal sheet 5' and the same sheetmetal 90 thimble-like member 6' which receives the lower end of the jacket, indicated at 7', the jacket being closed at the top by the cap 8'. In this modified form, however, the covering 9 of asbestos is eliminated and between 95 the smoke pipe, indicated at 4', and the jacket and thimble there is placed asbestos fiber 10 or other similar suitable material. In this construction a retaining ring 11 of sheetmetal is placed about the pipe 4', to 100 retain the packing 10 in position.

By this arrangement that part of the smoke pipe which is exposed to outside atmosphere will be protected against the chilling effect of the atmosphere so that the sudden condensation of the gases passing through the pipe will be avoided and it has been found in practice that this method en- 105

tirely eliminates the tendency for tar to accumulate in the pipe and to run down into the stove.

Having thus described my invention, I claim:

1. The combination, with the smoke pipe of a stove located in an inclosing structure, the upper part of which extends through an opening of said structure into outside atmosphere, of a thimble-like member secured to said structure about said opening and through which said pipe passes, and a single jacket of uniform diameter throughout for the upper end of said pipe spaced therefrom to form an air chamber, the upper end of said jacket being closed to outside atmosphere and the lower end fitted to said thimble with a tight fit to close said jacket to outer air at the lower end thereof, leaving the air chamber formed by said jacket in communication only with the air in said structure.

2. The combination, with a smoke pipe of a stove located in an enclosing structure, the upper part of which extends through an opening in said structure into outside atmosphere, of a thimble-like member secured to said structure about said opening and through which said pipe passes, a single jacket of uniform diameter throughout for the upper end of said pipe spaced therefrom to form an air chamber, a cap fitted to the extreme upper end of said jacket and perforated to receive said pipe with a tight fit to close the upper end of said jacket to atmosphere, the lower end of said pipe being fitted to said thimble with a tight fit to close said jacket to outer air at the lower end thereof, leaving the air chamber formed by said jacket in communication only with the air in said structure.

In testimony whereof, I have hereunto set my hand this 21st day of August, 1925.

LENA E. LINHART.
